UNITED STATES PATENT OFFICE

FINN T. IRGENS, OF MILWAUKEE, WISCONSIN, ASSIGNOR TO OUTBOARD MOTORS CORPORATION, OF MILWAUKEE, WISCONSIN, A CORPORATION OF MICHIGAN

FOLDING OUTBOARD MOTOR

Application filed October 12, 1929. Serial No. 399,128.

This invention relates to improvements in folding outboard motors.

It is the primary object of the invention to render a foldable motor more compact and easily portable than heretofore. It is a further purpose of the invention to provide a novel and improved arrangement for supporting the motor in a desired position whether folded or unfolded, and to provide means for holding accumulations of oil and waste products to prevent their discharge when the motor is not in use.

It is also my object to provide a novel and improved fuel tank mounting including a support for the tiller and carburetor and an enclosure for the carburetor inlet and magneto, whereby to muffle the sound of the air inlet and particularly to protect the operator against dirt and shocks and burns heretofore commonly experienced in the operation of outboard motors.

In the drawings:

Figure 1 is a side elevation of the motor as it appears when folded, the opened position of its lower end unit being illustrated in dotted lines.

Figure 2 is a rear elevation of the motor as it appears when folded, a portion of one of the mufflers being broken away.

Figure 3 is a plan view of the unfolded motor with the fly wheel and magneto and fuel tank removed to show the disposition of the fuel tank bracket, carburetor, and tiller handle support.

Figure 4 is a view taken in section in the plane indicated at 4-4 in Fig. 3.

Figure 5 is a detail in perspective of the muffler head shown in the other views.

Like parts are identified by the same reference characters throughout the several views.

The stream lined lower unit 10 of the motor is provided at its upper end with hinge knuckles at 11, and ears at 12 to which the clamping bolts 13 are pivoted. The lower end unit is of usual construction except that it is somewhat more elongated than has been the case heretofore in folding motors. Its elongation carries its stream lining well above the water line when the apparatus is in use.

The shaft housing 14, which terminates at 15 in a hinge fitting complementary to the upper end of the lower unit 10, is somewhat shorter than shaft housings heretofore employed. It is provided at 16 with notched 55 ears into which the swiveled lock bolts 13 are receivable. The swivel bearing 17 in which the motor turns as a unit for steering is provided with a rearwardly extending arm pivoted at 18 to the usual transom bracket 19. 60

Mounted on the upper end of the shaft housing 14 is a crank case 20 carrying the cylinders 21 and 22. The crank shaft 23 projects upwardly from the crank case and carries the usual fly wheel magneto 24 and start- 65 er disc 25.

Instead of the single transversely disposed muffler commonly used in two cylinder outboard engines, there are separate mufflers 30 provided for each of the cylinders 20 and 21. 70 These mufflers are individually bolted to the respective cylinders and project rearwardly in spaced relation. The space between them is sufficient to permit the passage of the lower unit 10 when such unit is folded as shown in Figs. 1 and 2. In the folded position of this unit the propeller 32 is disposed transversely immediately beneath the fly wheel 24 and the skeg 33 extends about the fly wheel to approximately the exact projection of the upper end of the drive shaft 23. 75

The hub of propeller 32 is peripherally grooved at 34 and is yieldably retained in the folded position of the parts by a spring detent 35. 80

It will be noted that the lower unit in its folded position occupies the space in which the fuel tank is commonly positioned. In the present motor the fuel tank 37 is moved to the front of the motor which position has 90 many advantages. Not only is a space provided for the folding of the motor to a more compact form, but in its forward position the fuel tank shields the fly wheel and the spark plugs and the hot cylinders of the engine, 95 thus preventing possible accident to the operator. Additionally, the fuel tank is positioned to intercept and protect the operator from oil thrown by the crank shaft or the magneto parts or fly wheel, and it also acts 100

as a baffle surrounding the air inlet to the carburetor hereinafter to be described, and minimizes noises commonly produced by air entering such carburetors.

- 5 In its forward position the fuel tank is protected from being struck upon the ground when the motor is being carried or laid down in its folded or unfolded condition. Furthermore, the cut-off valve 27 in the fuel line 10 to the carburetor is more conveniently accessible than has heretofore been the case. The fuel tank is also protected by its position from muffler heat. It is carried at its rear corners by angle brackets attached to jacketed 15 portions of the cylinders and its forward part is carried from the motor on a special bracket hereinafter described.

The timer control lever 38 is mounted on the rotatable base plate 39 of the fly wheel 20 magneto in the usual way but instead of projecting directly forwardly from such plate the lever 38 is extended upwardly in the arcuate channel between the fly wheel and the fuel tank 37 and is exposed for manipulation 25 above the top of the fuel tank. Plate 39 is provided at 40 with a toothed segment with which a spring finger 42 mounted on the carburetor and tiller bracket 43 is engaged to maintain the timer in its position to which it 30 is adjusted by lever 38.

The discharge ports of mufflers 30 instead of being located in the ends of the mufflers, are located at 44 in the peripheral side wall portions of relatively deep cup-shaped closures or heads 45 with which the respective mufflers are provided. It will be noted that in the folded condition of the motor it is supported at, three points by the muffler caps 45 and the hinged end of the lower unit 10. 40 When the lower unit is opened out as shown in dotted lines in Fig. 1 the motor may again be laid down upon three points, two of which comprise the muffler heads 45 and the third of which comprises the hub of propeller 32. In either position of the motor the caps 45 will be adapted to receive and retain against leakage any ordinary quantity of oil, water or waste products which remain in the mufflers.

The bracket 43 is unusual in that it supports 50 the fuel tank 37 and the tiller 50 while comprising in itself a carburetor. This bracket is integral with the front of the crank case at 51 and is fitted at 52 to the portion of cylinder 21 through which the mixture port enters crank case. Between these two points the bracket provides a passage 53 having its air inlet at 54 and including at 55 a cylindrical chamber in which the throttle valve operates. This valve comprises a rotary plug 56 bearing a partition 57 in the form of a cylinder subtending a chord of the cylindrical chamber 55. The float chamber 58 supplies a tubular nozzle 59 which enters the chamber 55 intermediate the air inlet and air outlet portions of passage

53 which lead to and from said chamber respectively.

The arrangement is such that by oscillation of plug 56 the operator may adjust the partition 57 either to partially or fully close either the inlet or the outlet portions of passage 53. If the plug is rotated counterclockwise from the full throttle position in which it is illustrated in Fig. 3 and Fig. 4, it will move across the air inlet portion of passage 75 53 thereby subjecting the jet 59 to the more or less unrelieved depression existing in the crank case, the effect being to "choke" the carburetor. If, on the other hand, the plug is rotated in a clockwise direction as illustrated in Fig. 3, the partition 57 will move across the outlet portion of passage 53 thereby more or less interfering with communication between chamber 55 and the crank case and thus "throttling" the carburetor. 80

A single control handle 60 used to produce the choking and throttling effects above described, projects beside the arm 63 of the bracket upon which the tiller 50 is mounted. Lever 60 carries a segment at 61 meshing with a small pinion at 62 on the shaft portion of valve plug 56. The full open throttle position may be defined by a spring pressed plunger 64 which co-acts with a notch in the bracket during the oscillation of lever 60 as 90 shown in Fig. 4.

The tiller 50 is fulcrumed upon the bolt 65 which is screwed into bracket arm 63 and also bears a brace 66 supporting the fuel tank 37. The arm 67 connected with the tiller grip 50 and disposed at right angles thereto, is provided at 68 with a spring pin which in the normal position of the tiller as indicated in dotted lines in Fig. 1 rests against shoulder 69 on the bracket. From the tiller position thus defined, the tiller may be oscillated upwardly thus permitting the operator conveniently to maintain control thereof on occasions when the entire motor is tilted about its bracket pivot 18 due to encountering some submerged obstruction. 100

When the spring pin 68 is pulled downwardly to clear shoulder 69 the tiller handle 50 may be folded down to the full line position in which it is illustrated in Fig. 1, and in this position the pin 68 is engaged in an aperture or socket 70 in the arm 63 of the combined tiller support and carburetor. The engagement of the pin in this socket holds the tiller substantially in alignment with the drive shaft of the motor and the shaft housing 14, thus enabling the tiller handle to be used as a carrying handle for the motor. It serves this function conveniently whether the motor is folded or unfolded. The location of this handle is sufficiently close to a vertical line through the center of gravity of the motor to facilitate use of the handle for carrying purposes and the lower unit 10 is so light that its disposition, whether open 110

or closed, makes little difference. The motor is very nearly in longitudinal balance beneath the horizontally disposed tiller handle 50 when its lower unit 10 is unfolded, and 5 is only slightly less in balance when the lower unit is folded.

It has not been thought necessary to describe in detail the provision of complementary water passages in the lower unit 10 and 10 the coupling portion 15 of the drive shaft housing, nor to illustrate the necessary provision of couplings on the exposed ends of the drive shaft portions in such unit and housing, since the present invention is not concerned with these features. So far as the 15 folding features of the present invention are concerned, they relate broadly to means whereby the motor is folded substantially in the exact center of its longitudinal length 20 whereby its overall dimensions when folded are less than would be the case if the joint were provided at any other point. As above pointed out this folding arrangement has been made practicable by a new disposition 25 of the gas tank and a new muffler arrangement, the other features described being worked out in harmony with this new disposition of the principal parts of the motor.

I claim:

30 1. A collapsible outboard motor comprising upper and lower units in hinged connection, the upper unit including an engine provided with a cylinder and a muffler, the muffler being so disposed that a portion of the lower unit may be folded about said hinged connection to lie laterally adjacent the muffler.

2. An outboard motor of the class described, comprising upper and lower units in 40 hinged relation, the upper unit comprising an engine provided with cylinders and a plurality of mufflers in spaced relation between which portions of said lower unit are folded.

3. An outboard motor of the class described, comprising upper and lower units adapted to be connected together in extended relation and alternatively to be disposed side by side, the upper unit comprising an engine, a forwardly disposed fuel tank and a pair of 50 rearwardly disposed mufflers between which portions of said lower unit may lie opposite said fuel tank.

4. An outboard motor comprising upper and lower units adapted to lie folded upon 55 each other and provided with means for connecting said units in extended relation, the upper unit comprising an engine having a fly wheel and a fuel tank disposed forwardly of said fly wheel and mufflers projecting rearwardly from said engine beneath said fly wheel and in spaced relation with each other, the lower unit carrying a propeller and a gear casing foldable between said mufflers with said propeller adjacent said fly wheel 60 and opposite said tank.

5. An outboard motor comprising upper and lower units adapted to lie folded upon each other and provided with means for connecting said units in extended relation, the upper unit comprising an engine having a fly wheel and a fuel tank disposed forwardly of said fly wheel and mufflers projecting rearwardly from said engine beneath said fly wheel and in spaced relation with each other, the lower unit carrying a propeller and a gear casing foldable between said mufflers with said propeller adjacent said fly wheel and opposite said tank, together with means for connecting said lower unit to the upper unit in the position in which its propeller is disposed as aforesaid. 70 75 80

6. A motor of the class described comprising hinged upper and lower units foldable upon each other, the upper unit including an engine and a fly wheel, and the lower unit including a propeller adapted in the folded position of the said units to lie immediately beneath the fly wheel, together with a detent yieldably engageable with a portion of said propeller and adapted to maintain said units 90 in their folded relation. 85

7. A motor of the class described comprising hinged upper and lower units foldable upon each other, the upper unit including an engine and a fly wheel, and the lower unit including a propeller adapted in the folded position of the said units to lie immediately beneath the fly wheel, together with a detent yieldably engageable with a portion of said propeller and adapted to maintain said units 95 100 in their folded relation, the propeller hub being grooved to receive said detent.

8. An outboard motor comprising hinged related upper and lower units, the upper unit including an engine provided with rearwardly projecting spaced mufflers adapted irrespectively of the position of the lower unit to provide support for said engine. 105

9. An outboard motor comprising hinged related upper and lower units, the upper unit including an engine provided with rearwardly projecting spaced mufflers adapted irrespectively of the position of the lower unit to provide support for said engine, said mufflers being closed at their ends. 110 115

10. An outboard motor comprising hinged related upper and lower units, the upper unit including an engine provided with rearwardly projecting spaced mufflers adapted irrespectively of the position of the lower unit to provide support for said engine, said mufflers being closed at their ends and provided with exhaust ports spaced from said ends whereby said ends are adapted to receive and retain waste materials falling in 120 125 said muffler when the engine is supported thereby.

11. In an outboard motor, the combination with an operatively connected engine and propelling lower unit, said engine comprising 130

- ing oppositely disposed cylinders and a forwardly projecting control handle, of individual mufflers connected with the respective cylinders and projecting rearwardly therefrom in spaced relation, said engine having a fuel tank disposed forwardly from said mufflers and extending clear across said engine above said handle.
12. In an outboard motor, the combination with an operatively connected engine and lower unit, said engine comprising oppositely disposed cylinders, of individual mufflers connected with the respective cylinders and projecting rearwardly therefrom in spaced relation, said engine having a fuel tank disposed forwardly from said muffler, and said lower unit being collapsible with respect to the engine to lie between said mufflers and opposite said tank.
13. An outboard motor having a two cylinder engine including opposite cylinders, a fly wheel thereabove, spark plugs projecting upwardly from said cylinders at each side of the fly wheel, and a fuel tank disposed about said fly wheel at the front thereof and extending in front of said spark plugs whereby to shield said plugs, cylinders, and fly wheel.
14. An outboard motor having a two cylinder engine including opposite cylinders, a fly wheel thereabove, spark plugs projecting upwardly from said cylinders at each side of the fly wheel, and a fuel tank disposed about said fly wheel at the front thereof and extending in front of said spark plugs whereby to shield said plugs, cylinders, and fly wheel from the operator, said cylinders having muffler means disposed at a point remote from said fuel tank.
15. An outboard motor having a two cylinder engine including opposite cylinders, a fly wheel thereabove, spark plugs projecting upwardly from said cylinders at each side of the fly wheel, and a fuel tank disposed about said fly wheel at the front thereof and extending in front of said spark plugs whereby to shield said plugs, cylinders, and fly wheel from the operator, said cylinders having muffler means disposed at a point remote from said fuel tank and adapted in a horizontal position of said motor to provide support for said engine.
16. An outboard motor having an engine provided with a fly wheel, a fuel tank at the front of the fly wheel, and a forwardly projecting bracket provided with a tiller handle and a support for said fuel tank, said bracket being connected with a fuel admission port leading to the interior of said engine and comprising a fuel admission passage leading to said port.
17. The combination with an outboard motor including an engine, of a tiller handle bracket having a hollow interior communicating with said engine for the admission
- of air thereto, means associated with said bracket for the carburetion of such air, and means on said bracket comprising a handle for the manipulation of the engine.
18. An outboard motor comprising in combination an engine having an admission port, a member providing an air passage leading to said port, a fuel duct leading to an intermediate portion of said passage, and a valve adjustable to restrict said passage alternatively at each side of said duct, said member being provided with a tiller handle for the manipulation of said motor.
19. An outboard motor comprising in combination an engine having an admission port, a member providing an air passage leading to said port, a fuel duct leading to an intermediate portion of said passage, and a valve adjustable to restrict said passage alternatively at each side of said duct, said member being provided with a tiller handle for the manipulation of said motor and said valve being provided with a handle projecting adjacent said tiller handle.
20. In an outboard motor the combination with a tiller handle pivotally connected with said motor and provided with means normally maintaining it in a position substantially at right angles to the motor shaft, of means for releasably securing said tiller in a position of substantial parallelism with said shaft whereby said handle may be used in the transportation of the motor.
21. In an outboard motor the combination with an engine and a drive shaft, of a tiller handle pivotally connected with said engine, and means for releasably maintaining said handle in a position substantially parallel with said shaft, whereby the tiller handle may serve as a carrying handle for the motor.
22. In an outboard motor the combination with an engine and a drive shaft, of a tiller handle pivotally connected with said engine, and means for releasably maintaining said handle in a position substantially parallel with said shaft whereby the tiller handle may serve as a carrying means for the motor, said means being adapted to define a second handle position in which said handle is maintained against movement below a line substantially at right angles to said shaft but is permitted movement upwardly from such a line.
23. A motor of the class described comprising hinged upper and lower units foldable upon each other, the upper unit including an engine and a fly-wheel, and the lower unit including a propeller and a section of the drive shaft housing, the upper unit having its parts at one side thereof spaced to provide a recess which receives the lower unit when the two units are folded upon one another with the propeller lying immediately beneath the flywheel and protected thereby.
